UNITED STATES PATENT OFFICE.

ELI MAYNARD LONG, OF GENEVA, NEW YORK, ASSIGNOR, BY MESNE ASSIGNMENTS,
TO THE STANDARD OPTICAL COMPANY, OF GENEVA, NEW YORK, A CORPORATION
OF NEW YORK (1924).

EDGE-GRINDING MACHINE FOR LENSES.

Application filed June 18, 1920. Serial No. 389,941.

To all whom it may concern:

Be it known that I, ELI M. LONG, of Geneva, in the county of Ontario, in the State of New York, have invented new and useful Improvements in Edge-Grinding Machines for Lenses, of which the following, taken in connection with the accompanying drawings, is a full, clear, and exact description.

10 This invention relates to certain improvements in edge-grinding machines for lenses of the class set forth in my pending application, Ser. No. 288,897, filed April 10, 1919, in so far that the main object is to bevel the 15 marginal edge of the lens for the reception of a similarly grooved rim.

In my pending application referred to, the axis of rotation of the rotary lens-holder is parallel with that of the grinding element to revolve the lens in a plane at substantially right angles to both axes, and while the mechanism shown therein for beveling the marginal edge of the lens is highly efficient and expeditious as compared with previous methods, it is found that the beveled faces of the grinding element near their junctions or points of contact one with the other tend to wear away faster than other portions of said faces owing to the relatively short line of contact of the edge of the lens with the grinding surface which tends to cut a relatively narrow annular groove or channel at the base of each beveled grinding surface and requires practically constant recutting or truing of said beveled surfaces in order to impart the desired bevel to the lens.

The main object of my present invention is to reduce these difficulties to a minimum by rotating the lens-holder and lens therein about an axis at an angle to that of the grinding element, or rather to rotate the lens in a plane at an angle to that of rotation of the beveled edges of the grinder, whereby opposite faces of the edge of the lens will be simultaneously brought into contact with both of the beveled grinding faces at different points in the circumferences of said beveled faces at opposite sides of the line of intersection of planes passing through the axes of the grinding element and lens-holder.

In other words, I have sought to rotate the grinding element and lens in different

planes intersecting each other at an angle 55 sufficient to cause one side of the lens to engage one of the beveled grinding faces at one side of the line of intersection, while the other side of the lens engages the other grinding edge at the opposite side of the 60 line of intersection, so that the edge of the lens adjacent the grinding surfaces will traverse greater portions of said surfaces than would be possible with the lens rotating in the same plane as that of the grinding element and results in keeping the 65 grinding surfaces true or at approximately the desired bevel without the aid of extra truing mechanism, except perhaps at relatively long intervals.

70 Other objects and uses relating to specific parts of the machine will be brought out in the following description.

In the drawings:

Figure 1 is a top plan of an edge-grinding machine embodying the various features 75 of my invention.

Figure 2 is a longitudinal vertical sectional view of the same mechanism showing the grinding element in elevation omitting the truing device.

Figure 3 is an enlarged horizontal sectional view of the rotary lens-holder and its driving mechanism.

Figure 4 is an enlarged side elevation of 85 the means for controlling the vertical lift of the lens-holder toward and from the grinder.

Figure 5 is a longitudinal sectional view 90 of the mechanism shown in Figure 4 except that the frame carrying the lens-holder is elevated.

Figure 6 is a top plan, partly in section, of a gear train for rotating the lens-holder and the means for lifting the lens-holder 95 frame.

Figure 7 is a detail edge view of the ratchet wheel and adjacent of the control pawl for the carriage lift.

Figure 8 is a top plan of a portion of the 100 grinder and lens engaged therewith.

Figure 9 is an enlarged sectional view through the grinding disks and clamping means therefor taken on line 9—9 Figure 2.

As illustrated, the machine comprises a 105 pair of similar relatively thin grinding disks —1— of any suitable diameter or material mounted coaxially upon a rotary hori-

horizontal shaft —2— which is journaled in suitable bearings —3— on a main supporting frame —4—, said grinding disks being circular and having their peripheries beveled inwardly toward each other at —5— to form a V-shaped groove —5'—, the meeting faces of said disks being held in slightly spaced relation by a circular disk or tiller —6— of any suitable material of substantially the same diameter as, or slightly less diameter than the base of the groove —5'—.

The grinding disks —1— and interposed disk —6— are firmly clamped together by opposed collars —7— and —7'—, on the shaft —2—, the collar —7— being provided with a suitable hub —8— extending into central openings in both of the disks —1— toward the opposite collar —7'— which is drawn toward the collar —7— by suitable bolts —9—, Figure 3.

The water for moistening the grinding disks is delivered by any suitable means, not shown, into an annular groove or recess —10— in the disk —7— and is carried by centrifugal force through passages —10'— to and within the grindstone disks and thence by the same force through the pores of said disks to the peripheral grinding faces where it may be wiped off by a sponge or other wiper, not shown, into a trough —11— and thence into a drain pipe —12—, Figure 2, the trough —11— serving merely to catch the waste water and grinding refuse.

The lens, as —a—, the peripheral edge of which is to be ground, is supported edgewise vertically by and coaxial with a rotary holder directly over the upper edges of the grinding disks —5—, but at an angle to the plane of revolution of said disks, said holder being free to move vertically or radially as portions of the edge of the lens at different distances from the axis of revolution are presented to the grinding surfaces, and is also free to swing laterally or axially as different portions of the edges of toric, cylindrical and other concave or convex lenses rotating in different planes contact with the grinding faces.

The holder for the lens comprises opposed coaxial clamping heads or collars —13— mounted end to end upon coaxial rotary shafts or spindles —14— and —14'— which, in turn, are journaled in suitable bearings —15— and —15'— on the free end of a vertically swinging frame or carriage —16— which is pivoted at —17— to a horizontally swinging frame —18—, the latter being pivoted at —19— to a vertically movable support —20— carried by a bracket —21— on the main supporting frame —4— to permit the perimeter of the lens to automatically adjust itself to the beveled grinding faces of the grinder during the grinding operation and to also permit the lens-holder and its

swinging supports to be adjusted vertically to compensate for varying diameters of the grinder resulting from wear or replacement by similar grinding disks.

The adjacent ends of the lens clamping collars —13— are provided with the usual leather or equivalent pads for frictional engagement with opposite faces of the lens to cause the latter to rotate with the collars and also to reduce the liability of breakage of the lenses when clamping them between the collars.

The shaft or spindle —14— carrying one of the lens-clamping collars —13— extends entirely through the central opening of a coaxial sleeve —22— and has its inner end operatively connected to the adjacent head —13— and its outer end provided with a gear —24— forming a part of a train by which rotary motion is imparted to the shaft —14— for rotating the lens-holder.

The outer end of the spindle —14— extends some distance beyond the gear —24— for receiving and supporting a lens form or pattern —25— which cooperates with a back rest —26— to cause the lens to be ground to a similar form, said pattern being held in place by a nut —27— engaging the outer threaded end of the spindle —14—.

The other spindle —14'— is journaled in its corresponding bearing —15'— and is secured in a socket in the adjacent end of the corresponding lens clamping head —13— so that the head and spindle may rotate together and also move axially, said spindle having a collar —28— secured thereto and provided with an annular groove —29— for receiving a shifting pin presently described.

This spindle —14'— is slidable axially in its bearing —15'— to force the corresponding lens clamping head —13— to and from its clamping position, but is normally held in its clamping position by a spring —30— which is interposed between the collar —28— and a bushing —32— in the outer end of the bearing —15'— as shown in Figure 3.

Suitable means is provided for withdrawing the spindle —14'— and its clamping head —13— from its clamping position against the action of the retracting spring —30— and for this purpose a hand lever —33— is pivoted at —34— to the periphery of the bearing —15'— and has its inner end provided with a pin —35— which engages in the groove —29— of the collar —28— and is movable in a lengthwise slot —36— in the bearing —15'— as shown in Figure 1.

The axis of rotation of the lens-holder is disposed at an angle to that of the grinding disks, and, therefore, at an angle to the plane of rotation of said disks, so that the grinding disks and lens rotate in different planes intersecting each other along a substantial

direct line between the axes of the rotary grinder and lens-holder and midway between the grinding disks, thereby causing the edge of said lens adjacent the grinder to simultaneously contact with both of the beveled grinding faces at different points in the periphery of the grinder at opposite sides of said line.

That is, by this angular relation of the axes of the grinder and lens-holder, one side of the edge of the lens is caused to engage one of the beveled grinding faces at one side of the line of intersection of the planes of rotation of said grinder and lens while the opposite side of the edge of the lens is caused to engage the other beveled grinding surface at the opposite side of said line of intersection and inasmuch as the portions of the beveled grinding surfaces engaged by the lens diverge outwardly, it is evident that the edge of the lens will be beveled to conform to the beveled edges of the grinder, thereby causing the edge of the lens to traverse practically the entire areas of the beveled faces of both grinding elements, and, in turn, will keep the grinding surfaces more closely to their original bevel as they wear away by contact with the lens.

Under these conditions, it is evident that the proper angle of the beveled grinding surfaces will be maintained for a much longer period of time without regrinding or truing and that both edges of the lens will be ground more rapidly and more evenly by reason of the longer lines of contact with the grinder than would be possible if the lenses were revolved in the same plane as that of the grinder.

In toric and other spherical or cylindrical lenses, particularly those of elliptical shape, different portions of the edges thereof are disposed in different planes and at different distances from the axis of rotation, and in order that the lens may automatically adjust itself to bring these different portions into proper grinding relation to the grinding surfaces, the supporting frame, as —16—, for the lens-holder is afforded a free vertical and lateral rocking movement as previously explained while the edge of the lens is held against the grinding surfaces by the weight of the frame and lens-holder thereon.

This support —16— preferably comprises a pair of oppositely disposed arms —16'— carrying the bearings —15— and —15'— in spaced relation at opposite ends of the lens clamping heads —13— and rigidly connected to each other by a cross-bar —37— so that both bearings carrying the lens-holder may be caused to move vertically in unison, the cross-bar —37— also serving as a handle by which said frame may be rocked upwardly and rearwardly at will about the axis of the pivots —17— through an arc of

90 degrees or more to withdraw the lens from the grinding element and allow the supporting frame for the lens-holder to assume a position of rest in its extreme up position as shown by full lines in Figure 5. 70

The horizontally rocking frame —18— is disposed in an upright position between forwardly projecting lugs —20— on the frame —20— and is held in this position by the pivotal pins or trunnions —19—, one of 75 which consists of a screw engaged in a threaded aperture in the adjacent lug —20— to take up wear and permit the frame —18— to be more easily and quickly assembled upon and removed from the frame —20—, the vertical swinging frame —16— being pivoted at its rear end to or upon forwardly projecting lugs —18'— of the frame —18— as shown more clearly in Figure 3.

The frame —20— is disposed in an upright position and is adapted to be adjusted vertically to produce a corresponding adjustment of the lens-holder to conform to varying diameters of the grinder, said frame being guided in its vertical adjustment and held in operative position by upright guide rods —40— and —40'— in spaced relation transversely of the machine and each passing through vertically registering apertures in said frame, said rods being supported in 95 suitable bearings or lugs —41— and —41'— on the bracket —21— a sufficient distance below and above the frame —20— to allow for the desired vertical adjustment of said frame between the bearings, one of said 100 guide rods, as —40— being provided with a threaded portion —42— engaging in a threaded aperture —43— in the lower side of the frame —20— and provided at its lower end with an angular head —44— 105 adapted to be engaged by a suitable wrench or other tool for rotating the screw and thereby effecting the desired vertical adjustment of the frame —20— and lens-holder carried thereby through the medium 110 of the frames —16— and —18—.

The rotary grinder and lens-holder are preferably power driven and for this purpose a shaft —45— is journaled in suitable bearings on the bracket —21— and provided 115 with a pulley —47— adapted to be connected by a belt —48— to any available source of power, not shown, said shaft being also provided with another pulley —49—, which is connected by a belt —50— to a 120 pulley —51— on the supporting shaft —2— for rotating the grinder.

A gear worm —52— is secured to the shaft —45— at substantially the longitudinal center of the machine or midway between the pulleys —47— and —49— and engages a gear —53— on an upright shaft —54—, which is journaled in vertically spaced bearings —55— and —55'— on the bracket —21—, the worm gear —53— being 130

provided with a vertically elongated hub having a gear worm —56— meshing with a worm gear —57—, which, together with a spur gear —57'— are rotatably mounted within the frame —20— and preferably upon a shaft —58—.

A cross shaft —59— is journaled in suitable bearings in the arms —16'— of the vertically rocking frame —16— and is driven by the gear —57'— through the medium of a train of, in this instance three, gears —60—, one of which is secured to the shaft —59— while the others are secured, respectively, to spindles —61— and —62— on the horizontally rocking frame —18—, the meshing faces between the gear —57'— and adjacent gear —60— being substantially coincident with the axis of movement of the horizontally rocking frame —18— as shown more clearly in Figs. —2— and —3— to permit said frame to rock through a limited arc without disengaging said gears.

The pivotal pins —17— are positioned between and parallel with the cross shafts —61— and —62— and are so related to the pitch diameters of the gears —60— on said shafts as to allow the frame —16'— to swing upwardly from a substantially horizontal to a substantially vertical position of temporary rest and during such movement to cause the gear on the shaft —59— to disengage from its companion gear —60— on the shaft —62— for automatically stopping the rotation of the lens-holder and permitting the finished lens to be removed and replaced by others to be finished, rotary motion being transmitted from the cross shaft —59— to another cross shaft —63— and thence to the gear —24— through the medium of a gear —63'— for rotating the lens-holder.

Pattern rest adjustment.

The lens to be beveled by the grinder previously described is usually cut or ground to approximately the desired form and size so that a relatively small number of turns of the lens against the grinder is sufficient to produce the desired bevel, and one of the objects of my present invention is to provide means whereby the lens-holder will be gradually and automatically lowered toward the grinder when it has been rotated a sufficient number of turns to produce the necessary bevel entirely around the periphery of the lens and for this purpose, the rest —26— is supported upon one end of a lever —64— which is fulcrumed intermediate its ends at —65— upon a portion of the horizontal rocking frame —18— to rock vertically. (See Fig. 4.)

The other end of the lever is provided with a bearing —66— adapted to be engaged by a rotary cam —67— which is mounted upon a horizontal shaft or stud —68— on

the frame —18— and is also secured to a coaxial rotary ratchet wheel —69— on the same stud so that the cam and ratchet wheel may rotate together, the shaft —59— being provided at one end with an eccentric pin —70— upon which is journaled one end of a pawl —71— having its other end adapted to successively engage the teeth of the ratchet wheel —69— as the pawl is reciprocated by the rotation of the eccentric —70— for rotating the cam step by step in the direction indicated by arrow *x*, Figure —4—.

That is the cam —67— will be rotated one tooth space of the ratchet wheel —69— at each revolution of the shaft —59— so that if there were forty teeth in the ratchet wheel —69—, it would be rotated one complete revolution at each forty revolutions of the eccentric —70— and if the ratio of speed between the lens-holder and eccentric is one to two, the lens-holder would be rotated twenty revolutions at each revolution of the ratchet wheel and would be sufficient to grind the edge of the lens to the desired bevels at one revolution of the ratchet wheel or cam —67—.

At the beginning of each revolution of the cam, its high point is engaged with the bearing —66—, and it, therefore, follows that as the cam is rotated, the lens rest —26—, together with the overlying portion of the frame or carriage —16— which supports the rotary lens-holder and pattern, will be gradually lowered, thereby causing the edge of the lens to be gradually beveled on both sides during one complete revolution or cycle of operation of the cam, or until the lowest point of said cam is registered with said bearing, at which time, the carriage —16— will be automatically rocked upwardly to a position of temporary rest, thereby withdrawing the lens-holder upwardly from the grindstone about the axis of the pivots —17— and simultaneously disengaging the gear connections between the spindles —59— and —62— to stop the rotation of the lens-holder and permit the withdrawal of the finished lens.

This upward movement of the carriage —16— is also utilized to shift the cam —67— from its low point to its high point of engagement with the bearing —66— by reason of the engagement of the pawl —71— with the ratchet —69— as the carriage —16'— is rocked upwardly.

Carriage lift.

The inner end face of the ratchet wheel —69— is provided with a notch or recess —72— for receiving the adjacent end of a sliding bolt —73— as the cam approaches the end of each cycle of rotation or when the low point of the cam is engaged with the bearing —66—, said bolt being spring-pressed toward the ratchet wheel by means

of a lever —74— and a spring —75— so as to normally ride against the inner face of the ratchet wheel during the cycle of rotation and into the recess at the end of said cycle.

The lever —74— is fulcrumed on the frame —18— near the bolt —73— to swing horizontally independently of the horizontal swinging movement of said frame and has its longer arm provided with an upstanding pin —76— for engaging and rocking another horizontal swinging lever —77— into the path of a revolving lifting member —78— on the shaft —62— against the action of a retracting spring —79— which is considerably lighter than the spring —75.

This lever —77— is pivoted to the under-side of the cross-bar —37— on the frame —16— and, it, therefore, follows that when it is moved laterally into the path of the continuously rotating member —78—, the frame —16— will be rocked upwardly and the gear —60— on the shaft —59— disengaged from that on the shaft —62—, which disengagement takes place when the frame —16— assumes a position slightly beyond a vertical, where it temporarily rests until returned by hand. (See Fig. 15.)

During this upward movement of the frame —16— the pawl —71— which is pivoted thereto, is shifted rearwardly and causes a corresponding rotary movement of the ratchet wheel —69— sufficient to shift the point of engagement of the cam —67— with the bearing —66— from the low point to the high or starting point and at the same time, the bolt —73— is forced out of the recess —72— by means of a cam face at one side of said recess.

As the frame —16— is rocked upwardly, the lever —77— is withdrawn from engagement with the pin —76—, but is frictionally held in lifting engagement with the member —78— against the action of the spring —79— by the weight of the frame until the latter assumes a substantially upright position, at which time, the lifting member —78— and lever —77— which swing in different arcs are disengaged to allow the lever —77— to be returned by the spring —79—.

The finished lens is then removed and replaced by another one to be finished, after which the frame —16— is lowered by hand ready for a repetition of the operations previously described.

A suitable truing device for keeping the beveled edges of the grinder at the desired angle is mounted upon the front portion of the machine and is provided with a pair of cutting bars —90— of carborundum, or other suitable material, adjustably mounted upon resilient supports —91— capable of lateral vibratory movement which is produced by means of an eccentric —92— and a pitman —93—, said eccentric being mount-

ed upon the front end of a shaft —94— having its rear end connected by a worm and gear —95— to the main driving shaft —45—, as shown more clearly in Figure 1—.

It is evident, however, that the various mechanisms for regulating the feed of the lens to the stone and for raising the carriage for the lens-holder may be varied in many ways, and, therefore, I do not wish to limit myself to the specific structural details shown and described.

What I claim is:

1. In a lens-edge-beveling machine, a rotary grinder having an annular groove, and means for rotatably supporting a lens edge-wise diagonally across the groove with its edge contacting at one side only of its axis of rotation against opposite walls of the groove for simultaneously beveling both corners of the edge of the lens.

2. In a lens-edge-beveling machine, a rotary grinder having opposed beveled faces, and means for rotatably supporting a lens at an acute angle to the axis of the grinder and its edge contacting at one side only of its axis against both of said beveled faces for simultaneously beveling both corners of the edge of the lens.

3. In a lens-edge-beveling machine, a rotary grinder having an annular groove, and means for rotatably supporting a lens edge-wise diagonally to and against opposite walls of the groove for simultaneously beveling both corners of the edge of the lens, said lens supporting means being movable transversely of the plane of rotation of the grinder and actuated by contact of the edge of the lens with opposite walls of the groove.

4. In a lens-edge-beveling machine, a rotary grinder having opposed beveled faces, and means for rotatably supporting a lens edge-wise diagonally to and against both of said beveled faces for simultaneously beveling both corners of the edge of the lens, said lens-supporting-means being movable about an axis parallel with the plane of rotation of the grinder and actuated by contact of the edge of the lens with the beveled faces of the grinder.

5. In a machine for beveling the edges of lenses, the combination of a rotary grinder having opposed beveled faces, a rotary lens-holder and a support therefor hinged to swing toward and from and transversely of the periphery of the grinder by contact of the lens with said beveled faces, said lens-holder being journaled on the support to rotate about an axis diagonally to the plane of rotation of the grinder for holding the lens edge-wise against both of said beveled faces.

6. In a machine for beveling the edges of lenses, a rotary grinder having opposed beveled faces, means for rotatably support-

- 6 ing a lens edgewise diagonally to and against both of said faces and movable transversely of the plane of rotation of the grinder by contact with the edge of the lens with said beveled faces, means for rotating the lens and means actuated by the second named means for moving the first named means away from the grinder when the lens has been rotated a predetermined number of revolutions.
- 10 7. In a lens edge beveling machine, a grinding element having opposed abrasive faces, a rotary lens holding element for supporting a lens edgewise diagonally across and against both of said faces, the engagement of the lens with said faces causing one element to automatically shift in the direction of the axis of the lens holding element to compensate for variations in the planes of rotation of different portions of the edge of the lens.
- 15 8. In a lens edge beveling machine, a rotary grinding element having opposed beveled faces, and a rotary lens-holding element having its axis extending diagonally across the face of the grinder and supporting a lens edgewise against both of said faces, one element being movable axially relatively to the other element by the engagement of the edge of the lens with the beveled grinding faces when different positions of the edge of the lens rotate in different planes.
- 20 9. In a lens edge beveling machine, a grinding element having opposed abrasive faces, a rotary lens holding element for supporting a lens edgewise diagonally across and against both of said faces, the engagement of the lens with said faces causing one element to automatically shift in the direction of the axis of the lens holding element to compensate for variations in the planes of rotation of different portions of the edge of the lens, means for rotating the lens holding element, and means actuated by the last named means for moving one of the elements away from the other element a sufficient distance to disengage the lens from the grinder at the end of a predetermined number of revolutions of the lens-holding element.
- 25 10. In an edge grinding machine for lenses, a rotary lens holder, and a rocking support therefor adapted to move the lens holder toward the grinder as the edge of the lens is ground away, a rotary driving element, a gear train partly mounted upon said rocking support for transmitting motion from the driving element to the lens holder while the lens is in contact with the grinder and means actuated by said gear train at the end of a predetermined number of revolutions of the lens holder for rocking said support and lens holder thereon away from the grinder, said rocking support being so related to the gear train as to disconnect
- 30 parts of the gear train from other parts thereof when the support is rocked away from the grinder.
- 35 11. In an edge grinding machine for lenses, the combination of a grinder rotatable about a horizontal axis and provided with opposed beveled grinding faces, means for rotatably supporting a lens edgewise diagonally across and against both of said beveled faces, and driving means for the rotary grinder and lens holder said supporting means being free to move in reverse directions transversely of the grinding faces by contact of the edge of the lens therewith.
- 40 12. In a machine for beveling the edge of a lens, a grinder rotatable about a horizontal axis and provided with opposed beveled faces, a support for a lens-holder movable about a vertical axis, a lens holder mounted on said support to rotate about an axis diagonal to the plane of rotation of the grinder and supporting a lens edgewise diagonally across and against both of said bevel faces, the engagement of the edge of the lens with the bevel faces serving to shift the support about its vertical axis to compensate for variations in the planes of rotation of different portions of the edge of the lens.
- 45 13. In an edge grinding machine for lenses, the combination of a rotary grinder having opposed beveled grinding faces, means for rotatably supporting a lens edgewise diagonally across and against both of said faces, said means being free to move radially and axially of the grinder and actuated in both of the last named directions by contact of the lenses with the beveled grinding faces, driving means for rotating the lens, a stop for limiting the movement of the lens supporting means toward the axis of the grinder and means actuated by said driving means for gradually moving the stop toward the axis of the grinder as the lens is ground away.
- 50 14. In an edge grinding machine for lenses, the combination of a rotary grinder having opposed beveled grinding faces, means for rotatably supporting a lens edgewise diagonally across and against both of said faces, said means being free to move radially and axially of the grinder and actuated in both of the last named directions by contact of the lens with the beveled grinding faces, driving means for rotating the lens, and means actuated by said driving means for stopping the rotation of the lens at the end of a predetermined number of revolutions thereof.
- 55 15. In an edge grinding machine for lenses, the combination of a rotary grinder having opposed beveled grinding faces, means for rotatably supporting a lens edgewise diagonally across and against both of said faces, said means being free to move

- radially and axially of the grinder and actuated in both of the last named directions by contact of the lenses with the beveled grinding faces, driving means for rotating the lens, a stop for limiting the movement of the lens supporting means toward the axis of the grinder, means actuated by said driving means for gradually moving the stop toward the axis of the grinder as the lens is ground away, and means actuated by said driving means for moving the lens supporting means away from the grinder at the end of a predetermined number of revolutions.
16. In an edge grinding machine for lenses, the combination of a grinder rotatable about a horizontal axis and provided with opposed beveled grinding faces, means for rotatably supporting a lens edgewise diagonally across and against both of said faces directly over the axis of the grinder, said supporting means being movable radially and axially of the grinder by contact of the edge of the lens with the grinding faces, driving means for rotating the lens, and means actuated by said driving means for moving the lens supporting means away from the grinder at the end of a predetermined number of revolutions of the lens.
17. In an edge grinding machine for lenses, the combination of a grinder rotatable about a horizontal axis and provided with opposed beveled grinding faces, means for rotatably supporting a lens edgewise diagonally across and against both of said faces directly over the axis of the grinder, said supporting means being movable radially and axially of the grinder by contact of the edge of the lens with the grinding faces, and driving means for rotating the lens.
18. In an edge grinding machine for lenses, the combination of a grinder rotatable about a horizontal axis and provided with opposed beveled grinding faces, means for rotatably supporting a lens edgewise diagonally across and against both of said faces directly over the axis of the grinder, said supporting means being movable radially and axially of the grinder by contact of the edge of the lens with the grinding faces, driving means for rotating the lens, means for limiting the movement of the lens supporting means toward the axis of the grinder, and means actuated by the driving means for adjusting said limiting means a definite amount at each revolution of the lens to allow the lens supporting means to move gradually toward the axis of the grinder, and means actuated by the driving means for adjusting said limiting means a definite amount at each revolution of the lens to allow the lens supporting means to move gradually toward the axis of the grinder.
19. In an edge grinding machine for lenses, the combination of a grinder rotatable about a horizontal axis and provided with opposed beveled grinding faces, means for rotatably supporting a lens edgewise diagonally across and against both of said faces directly over the axis of the grinder, said supporting means being movable radially and axially of the grinder by contact of the edge of the lens with the grinding faces, driving means for rotating the lens, means for limiting the movement of the lens supporting means toward the axis of the grinder, means actuated by the driving means for adjusting said limiting means a definite amount at each revolution of the lens to allow the lens supporting means to move gradually toward the axis of the grinder, and means actuated by the driving means for moving the lens supporting means away from the grinder at the end of a predetermined movement of revolutions of the lens.

In witness whereof I have hereunto set my hand this 10th day of June, 1920.

ELI MAYNARD LONG.
